Ohio, as trustee

Application July 25, 1933, Serial No. 682,051

4 Claims. (Cl. 309—12)

This invention relates to pistons for internal combustion engines and the like, and particularly to pistons composed of aluminum alloy or other metal alloy having a higher coefficient 5 of thermal expansion than the material of the cylinder in which the piston is to operate.

The principal object of this invention is to provide a relatively simple and cheap piston construction which may be fitted when cold to a 10 cylinder with a sufficiently small clearance to avoid piston slap and to reduce oil pumping and which will yield to permit thermal expansion without binding in the cylinder while at the same time being designed to provide ample bearing 15 surfaces for transmitting the thrust loads to the cylinder walls without excessive friction at isolated points and to permit a free flow of heat from the piston to the cylinder walls and to operate in a cylinder at all times without excessive 20 friction and without premature fatigue failure.

The present invention consists primarily in a 25 novel arrangement of slotting a piston of the full trunk type and providing means for yieldably pressing the slotted parts in such a manner that the piston will fit the cylinder without slapping or rattling at all temperatures and will also reciprocate freely without binding at all temperatures. One object of this invention is to provide 30 a piston with a skirt slotted on one side only and the slotted portions pressed out yieldably in such a manner that the piston when cold will fit the cylinder with a relatively close clearance along the diameter perpendicular to the wrist pin bosses and with a relatively large clearance along the 35 diameter parallel to the wrist pin axis and with a clearance increasing in both directions from the center of the slotted face more rapidly than from the center of the opposite face so as to provide a relatively wide bearing on the unslotted 40 face when the piston is cold to prevent lateral movement of the piston along the wrist pin axis. Other objects of the invention are to avoid fatigue of the slotted portions of the piston by initially yieldably pressing the slotted portions 45 outwardly; to apply the yieldable pressure to the slotted portion of the skirt through a relatively wide vertical range in the zone of the application of the lateral thrust; to mount an expander element in a piston in such a manner that thermal 50 expansion of the head will reduce the amount the skirt is held expanded; and to provide a simple and cheap expander element which may be easily constructed and assembled in the piston.

55 Other objects and advantages of this inven-

tion relating to details of construction and economies of manufacture will appear hereinafter.

In the accompanying drawing which illustrates a preferred embodiment of the invention:

Figure 1 is an elevational view of a piston constructed in accordance with this invention; 5

Figure 2 is an elevational view taken from a point at right angles to Figure 1;

Figure 3 is a cross section taken on the line 3—3 of Figure 1;

Figure 4 is a view corresponding to Figure 3 of 10 a modified embodiment of the invention.

Referring to the drawing the numeral 10 designates the head of the piston which is preferably constructed of aluminum alloy or similar light 15 metal. The head is formed with a depending ring flange 11 which may be provided in the usual manner with a series of ring grooves 12. The piston is preferably initially cast in the form of a full trunk type piston including a cylindrical 20 skirt 13 integral with the lower edge of the ring flange and having opposed wrist pin bosses 14 formed therein. Preferably the piston is also cast with relieved areas 15 in the region of the 25 wrist pin bosses. After casting the piston is completed by machining operations.

The skirt of the piston is partially separated from the head by a horizontal arcuate slot 16 which is preferably cut through the lower-most ring groove as shown and extends on one side 30 of the piston through less than 180 degrees with its ends spaced from the vertical plane through the wrist pin axis. Preferably the slot terminates in holes 17 drilled through the piston wall. The portion of the wall of the piston separated 35 from the head by the horizontal slot 16 constitutes one thrust face and is designated by the numeral 18. The opposite side of the piston, forming the thrust face 19 preferably remains integrally attached to the head. 40

The thrust face 18 is rendered yieldable by means of a substantially vertical slot 20 cut through this thrust face at about its center intersecting the horizontal slot 16 and preferably extending completely through the height of the 45 skirt as illustrated in Figure 2. This arrangement of slots with the horizontal slot 16 separating the upper edge of the thrust face 18 from the head and the substantially vertical slot 20 dividing the thrust face 18 provides a pair of 50 relatively yieldable leaves which may be flexed inwardly toward each other to reduce the diameter of the skirt at all points through the vertical height and prevent binding of the piston in the cylinder. 55

The ring flange 11 of the piston is preferably ground to a sufficiently small diameter so that it does not contact the cylinder walls at any temperature in accordance with the usual practice. 5 The skirt of the piston is preferably ground to a cylindrical contour so that all portions of the skirt are circular in horizontal section except for the relieved areas 15 in the region of the wrist pin bosses. The skirt is preferably ground to a diameter small enough to leave a large clearance from the wall of the cylinder in which the piston is designed to operate; that is, a clearance corresponding to about the clearance that would be necessary for a full trunk type piston having no slotted or yieldable portions.

A spring expander 21 which may be constructed of any suitable metal having the necessary resilience and fatigue resistance such as spring steel is assembled within the piston after the completion of the grinding and slotting. The expander is preferably of ferrous metal so as to expand but slightly when heated. The expander 21 is of substantial vertical height as illustrated in Figure 1 and is curved to provide a central portion 22 to engage the interior of the wall of the thrust face 18 at about its center and curved ends 23 to seat against the wrist pin bosses 14. Preferably the wrist pin bosses 14 are formed with seats 24 curved to fit the ends 23 of the expander throughout its length. Integral lugs or bosses 25 may also be formed at the top and bottom edges of the seats 24 to embrace the ends 23 of the expander and retain the same against vertical movement or dislocation.

35 The expander 21 is arranged to press against the inner surface of the wall of the thrust face 18 with sufficient force to initially spread the separated leaves of the thrust face 18 outwardly as illustrated in Figure 3. The piston may then be assembled within a cylinder, indicated in cross section at C in Figures 3 and 4, with the centers of the two thrust faces 18 and 19 in close clearance relation to the wall of the cylinder. The thrust face 19 is curved with a slightly greater 45 degree of curvature than the wall of the cylinder, since this thrust face has been ground to a circular contour about the center 26 as indicated in Figure 3 which is spaced slightly toward the thrust face 19 from the center line or axis of the cylinder 27. Accordingly, the clearance of 50 the thrust face 19 from the cylinder wall increases slightly in both directions from the center of the thrust face as shown in Figure 3. The thrust face 18 is pressed out of its circular contour by the expander 21 so that this thrust face has an ovate sectional contour. The clearance of the thrust face 18 increases in both directions from its vertical center relatively rapidly 55 so that a relatively large clearance exists between the cylinder wall and the thrust face 18 at the adjacent ends of the relieved areas 15.

The piston is fitted to the cylinder in this manner while the parts are cold. Piston slap in the direction perpendicular to the wrist pin axis is 65 avoided by the relatively close clearance at the ends of this axis. Lateral movement of the piston along the wrist pin axis is prevented by the relatively small clearance between the thrust face 19 and the cylinder wall which is sufficiently 70 small at the adjacent ends of the relieved areas 15 to prevent an audible slap in the event the piston moves along the wrist pin axis within the cylinder. As the piston heats up to working temperature the head and ring flange expand and 75 while retaining their circular contour become

larger in diameter. Exactly the same action takes place in the portion of the skirt integrally connected to the head which includes the thrust face 19 and the portions of the skirt carrying the wrist pin bosses 14. The entire piston is thereby caused to move to the right in the cylinder as seen in Figure 3 until the center 26 coincides with the axis of the cylinder 27. This movement and expansion of the parts is permitted by the yieldable leaves of the thrust face 18 which are pressed inwardly toward each other against the resilience of the spring 21, partially closing the slot 20 from its expanded position. The curved ends 23 of the expander 21 are allowed to slide on the seats 24 on the wrist pin bosses to accommodate this movement of the leaves of the thrust face 18, or the expander may simply flex sufficiently to accommodate the movement of the ends. In either event the movement of the yieldable leaves is resisted by the resiliency of the expander 21. Thus when the piston reaches full operating temperature it returns to a true circular sectional contour corresponding to the cylinder but with a diameter greater than that to which it was initially ground so that the piston fits the cylinder throughout its circumference in substantially the same manner as a full trunk piston. The substantially vertical slot 20 may be made extremely narrow initially so that it is opened when the piston is cold by the expander 30 21 and is substantially closed when the piston reaches full operating temperature.

The expander 21 is preferably made relatively stiff so that it yields but slightly under the lateral thrusts of the piston against the cylinder wall due 35 to the angularity of the connecting rod so as to avoid excessive flexing and consequent fatigue of the separated portions of the thrust face 18 and the expander 21. When the piston expands the bosses 14 are moved apart slightly due to 40 the increase in diameter of the piston in the direction of the wrist pin axis. This separation of the bosses correspondingly separates the ends 23 of the expander 21 which are seated in the opposite bosses and thereby permits the separated portions of the thrust face 18 to move inwardly through a greater distance than is permitted when the piston is cold. Thus the necessary flexibility is provided at all temperatures, although the stiffness of the expander 21 prevents the separated portions of the thrust face 18 45 from being pressed completely back to their initial truly circular contour until the bosses 14 have been separated slightly by the thermal expansion. In other words the stiffness of the expander 21 is such that the distance through which the separated portions of the thrust face 18 may yield under the lateral thrusts to which the piston is subjected is substantially less at any given 50 position of the wrist pin bosses than the total distance through which the separated portions move during the heating up of the piston to full operating temperature. Normally the piston is assembled within the cylinder so that the maximum thrust, or in other words, the lateral thrusts 55 of the power stroke, are taken by the thrust face 19 while the substantially smaller thrusts of the compression stroke and the inertia of the piston are taken by the thrust face 18.

A slightly modified embodiment is illustrated in 70 Figure 4 in which the skirt of the piston instead of being ground to a circular sectional contour initially is cam ground to an ovate sectional contour with the major axis perpendicular to the wrist pin bosses and a greater increase in clear- 75

5 ance in both directions from the center of the minimum thrust face 18 than at corresponding points on the maximum thrust face 18, as disclosed in the copending application of Frank 10 Jardine, Serial No. 619,947, filed June 29, 1932. The operation of this form of the piston is substantially the same as that previously described except that the expander 21 instead of initially 15 forcing the leaves of the thrust face outwardly through a sufficient distance to provide the desired close clearance at the centers of the thrust faces acts primarily to restrain these leaves of the thrust face 18 and thereby does not initially stress the metal of the thrust face to such a great extent. The expander 21 serves to prevent 20 excessive flexing of the leaves of the thrust face 18 under lateral thrust which would otherwise be permitted with the slot cut completely through the height of the skirt as illustrated.

25 It will be clear that the arrangement of the expander element 21 may, if desired, be incorporated in any type of slotted piston in engagement with the slotted part to perform the functions described. Various other rearrangements 30 of parts and modifications of structural detail of either the piston or expander may be resorted to without departing from the scope of the invention as defined in the following claims.

I claim:

30 1. An internal combustion engine piston including a head having a substantially cylindrical depending ring flange, and a skirt partially integral with the lower edge of said ring flange, and carrying aligned wrist pin bosses, said skirt being formed with opposed thrust faces between said bosses, one of said thrust faces being separated at its upper edge from said head and having a substantially vertical slot formed therein, said skirt being initially ground to a substantially circular sectional contour with a diameter substantially less than the diameter of a circular cylinder in which the piston is to operate, and means pressing said slotted thrust face outwardly 40 beyond its initial contour so that the piston when cold fits the cylinder with a relatively small clearance at the ends of the diameter perpendicular to the wrist pin axis, said means being yieldable so that said piston may return to a substantially circular contour with a relatively small 45 clearance from said cylinder throughout its circumference when said piston is heated to operating temperature.

2. An internal combustion engine piston composed of light metal alloy, including a head having a substantially cylindrical depending ring flange and a skirt partially integral with the lower edge of said ring flange and carrying aligned wrist pin bosses, said skirt being formed with opposed thrust faces between said bosses, one of 50 said thrust faces being separated at its upper edge from said head and having a substantially vertical slot formed therein, said skirt being initially ground to a substantially circular sectional contour with a diameter substantially less than the 55 diameter of a circular cylinder in which the piston is to operate, and means composed of ferrous

metal pressing said slotted thrust face outwardly beyond its initial contour so that the piston when cold fits the cylinder with a relatively small clearance at the ends of the diameter perpendicular to the wrist pin axis, said means being yieldable so 5 that said piston may return to a substantially circular contour with a relatively small clearance from said cylinder throughout its circumference when said piston is heated to operating temperature. 10

3. An internal combustion engine piston for operation in a circular iron cylinder of an internal combustion engine, said piston being composed of aluminum alloy and including a head having a ring flange, a skirt partially integral at 15 its upper edge with the lower edge of said ring flange having aligned wrist pin bosses formed therein and including opposed thrust faces intermediate said wrist pin bosses, one of said thrust faces being separated at its upper edge from said ring flange and being formed with a substantially vertical slot, said skirt being ground to a substantially circular sectional contour with a diameter excessively less, when the piston is cold, than the diameter of the engine cylinder in which 20 the piston is to operate, when cold, and means pressing said slotted thrust face outwardly beyond its initial contour and into an oval sectional contour, said means being arranged to react against said wrist pin bosses so as not to distort 25 the other of said thrust faces, said skirt when cold fitting the engine cylinder with a relatively close clearance at the ends of a diameter perpendicular to the wrist pin axis and with said slotted thrust face having a minimum clearance 30 at its center, small enough to prevent piston slap and a progressively increasing clearance with respect to the cylinder at points spaced on each side of the center, and with the other thrust face having a minimum clearance at its center and a 35 progressively increasing clearance from the cylinder wall at points spaced on each side of its center substantially less than the clearance of corresponding points on the slotted thrust face and insufficient to permit piston slap from lateral 40 play of the piston along the wrist pin axis, said means being yieldable to permit said slotted thrust face to return to its initial contour and said piston skirt fitting the engine cylinder with a 45 relatively close clearance throughout its periphery when said piston is heated to full operating 50 temperature.

4. The method of making a light metal piston for internal combustion engines which comprises 55 machining the piston by grinding and cutting operations to form a skirt having cylinder engaging surfaces all of which have a circular sectional contour, and a slotted portion on one side between the wrist pin bosses, and resiliently securing said slotted side of the skirt pressed outwardly at its center with respect to the wrist pin bosses in such a manner as to change the sectional contour of the slotted side to a semi-elliptical sectional contour with its major axis perpendicular to the wrist pin axis. 60
